189,603

COMBINED COOKING AND WARMING CABINET

Robert Lee Paschal, 5028 Old Mansfield Road,
Fort Worth, Tex.

Filed Aug. 27, 1958, Ser. No. 52,406

Term of patent 7 years

(Cl. D81—10)

Fig. 1

Fig.2

Fig.3

Fig.4

Fig.5

Fig.6

Figure 1 is a perspective view of a combined cooking and warming cabinet embodying my new design.

Figure 2 is a top plan view thereof.

Figure 3 is a front elevational view thereof.

Figure 4 is a rear elevational view of my new design.

Figure 5 is a left end view thereof, and

Figure 6 is a right end view of my combined cooking and warming cabinet.

Parts of the cord are broken away for purposes of convenience of illustration.

The dominant features of my design reside in the portions shown in full lines.

I claim:

The new and ornamental design for a combined cooking and warming cabinet, as shown and described.
